UNITED STATES PATENT OFFICE

ANDREA GRAZIANI, OF CAMDEN, NEW JERSEY

HEAT CONDUIT AND PROTECTOR THEREFOR

Application filed August 27, 1930. Serial No. 478,031.

My invention relates to new and useful improvements in a heat conduit and protector therefor, particularly adapted for use in connection with electric heaters as used in railway cars, and has for one of its objects to provide an exceedingly simple and effective device of this character which may be readily built into a car during the manufacture of the latter or substituted for the present-day conduits.

Another object of the invention is to provide a conduit which will direct the heat in opposite directions in order that the benefits from a single heater may be obtained by the occupants of two adjacent seats.

A further object of the invention is to provide a protector for the conduit which may be readily applied thereto and prevent any débris reaching the electric heater during the time the interior of the car is being sanded prior to painting.

A still further object of the invention is to provide a combination of a heat conduit to be mounted in a car so as to run lengthwise thereof along a small area of a side wall, preferably between two seats and open at both ends and a protector having sections to cover the ends of the conduit and a connecting section joint with the two first mentioned.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:—

Fig. 1 is a fragmentary longitudinal sectional view of the body of a railway passenger car showing my invention applied to the interior thereof and illustrating in dotted lines the normal relative positions of a number of the car seats and further a portion of the cementitious floor being broken away to clearly illustrate the position of the conduit, one of which is also partly broken.

Fig. 2 is a vertical sectional view of Fig. 1 on a line 2—2 of Fig. 1.

Fig. 3 is an enlarged perspective view of the conduit looking toward the front thereof.

Fig. 4 is a similar view looking toward the back of the same.

Fig. 5 is a perspective view of the protector for use in combination with the conduit when sanded operations are to be carried out.

In carrying out the invention as herein embodied, 6 represents the body of a railway passenger car or coach including a side wall 7, generally produced from sheet steel and constructed to provide inner and outer skins, and a floor 8 at least a portion of which is of cementitious material.

The electric heaters (not shown) are generally located between the inner and outer skins of the side walls adjacent the floor and the inner skin of said side walls have openings in the region of the electric heaters to permit of egress of the heat or the outward flow of heated air as it circulates through the car.

Each opening in the inner skin of the side walls of the car which is in the region of an electric heater has the panel 9 of my invention disposed thereacross and secured to the inner skin of the side wall in any suitable manner as by welding, rivets, screws or other fastening devices and said panel has an aperture 10 therethrough across which is disposed suitable foraminous material 11, such as a strip of wire screening in order to prevent foreign material from coming in contact with the heater as well as preventing persons poking sticks or other objects into the heater.

On the outer face of the panel is mounted a rectangular conduit 12 open at the back so that the interior thereof is in communication through the aperture 10 in the panel with the compartment holding the electric heater and also open at both ends to permit egress of the heated air. Both ends of the conduit are reduced in size to form spouts 13, the top and bottom wall of which are substantially evenly disposed beyond the top and bottom walls of the main body of the conduit with

the rear walls of the spouts spaced from the panel while the front wall of said spouts may coincide with the front wall of the main body portion of the conduit as clearly shown in Fig. 3.

When a conduit is in place and an electric heater is put in operation, the heated air will pass through the opening 10 in the panel 9 into the main body portion of the conduit and thence out of the open ends into the car and since the open ends of the conduit are generally disposed beneath or adjacent two car seats, the occupants of said seats will immediately obtain the benefits from the heated air.

In order to protect the electric heater from damage during sanding operations, I provide a protector 14 formed of suitable stout textile material which will exclude sand and dust and this is so fashioned as to provide cover or closure sections 15 so as to fit over and pocket the spouts 13 of the conduit, the said covers or closures being connected with or attached to the connecting strip 16 which is of sufficient length to extend from one end to the other of the conduit across or lengthwise of the outer wall of said conduit and suitable pliable fastening members 17 are secured to the covers so that when the protector is in place, these fastening members may be wrapped around the spouts and tied whereby the protector will be securely held in place against the blasts of air and sand or other cleaning substances under pressure.

From the foregoing, it will be noted that when the cover sections 15 of the protector are in place, the edges thereof will be behind the end walls of the conduit body forming parts of the spouts of reduced size and therefore protected from the blasts of air.

The conduit being of smaller width than the panel when the device is assembled in a railway car and the floor of the latter poured or laid, the lower edge of the panel will be covered and the bottom wall of the conduit will practically lie upon the upper surface of the floor as clearly shown in Fig. 1, but since the bottom walls of the spouts are inside from the bottom of the conduit, said spouts will be spaced from the floor to permit application of the protector.

Of course I do not wish to be limited to the exact details of construction as herein shown, as these may be varied within the limits of the appended claims without departing from the spirit of my invention.

Having thus fully described my invention, what I claim as new and useful is:—

1. In a heat conduit and protector therefor, a panel for disposition across an opening leading from a compartment containing an electric heater, said panel having an opening therethrough, a conduit supported by said panel and having an open portion in com-

munication with the opening in said panel, the ends of said conduit being reduced in size and being open for the exit of heated air, a protector of flexible material including covers to pocket the reduced end of the conduit and temporarily close the same, a connecting strip to which the covers are attached and pliable fastening devices secured to said covers and adapted to be wound about said covers when on the reduced ends of the conduit to hold said protector in place.

2. The structure set forth in claim 1 in combination with a strip of foraminous material disposed across the opening through the panel and secured to said panel to prevent the insertion of objects through the opening in said panel.

In testimony whereof, I have hereunto affixed my signature.

ANDREA GRAZIANI.
